COMBINED COOKING APPLIANCE AND DISPLAY CASE

Eugene Buday, Livingston, N.J., assignor to Stainless
Food Equipment Co., Newark, N.J., a corporation of New Jersey

Filed Oct. 30, 1958, Ser. No. 53,220

Term of patent 7 years

(Cl. D81—10)

The figure is a perspective view of a combined cooking appliance and display case embodying my new design. The side not shown is substantially the same in appearance as the side shown, and the rear is substantially plain.

I claim:

The ornamental design for a combined cooking appliance and display case, as shown and described.
